UNITED STATES PATENT OFFICE.

ERNEST K. MCCOY, OF PORTSMOUTH, VIRGINIA, ASSIGNOR OF ONE-HALF
TO JOHN C. TYLER, OF PORTSMOUTH, VIRGINIA.

SANDING-TOOL.

No. 819,578.

Specification of Letters Patent.

Patented May 1, 1906.

Application filed September 18, 1905. Serial No. 279,011.

To all whom it may concern:

Be it known that I, ERNEST K. McCoy, a citizen of the United States, residing at Portsmouth, in the county of Norfolk and State of Virginia, have invented certain new and useful Improvements in Sanding-Tools; and I do declare the following to be a full, clear, and exact description of the invention, such as will enable others skilled in the art to which it appertains to make and use the same.

My invention relates to improvements in rasping and sanding tools, and more particularly to a device of this character which may be applied to a portable power-drill or similar tool.

The object of the invention is to provide a device or attachment of this character which will be simple in construction, durable and efficient in operation, and comparatively inexpensive to manufacture.

With the above and other objects in view the invention consists of certain novel features of construction, combination, and arrangement of parts, as will be hereinafter more fully described, and particularly pointed out in the appended claims.

In the accompanying drawings, Figure 1 is a longitudinal sectional view through my improved sanding-tool, showing the same applied to a portable pneumatic or power drill. Fig. 2 is an end elevation of the same. Fig. 3 is a vertical transverse sectional view taken on the plane indicated by the line *a a* of Fig. 1. Fig. 4 is a detail view showing the manner in which the cylindrical body of the attachment may be adjusted to clamp the sanding or rasping face thereon. Fig. 5 is a perspective view of the rasping-cylinder which may be substituted for the sanding-cylinder shown in Figs. 1, 2, and 3, and Fig. 6 is a longitudinal sectional view through a slightly modified form of the invention.

My improved rasping and sanding tool 1 is in the form of an attachment which may be secured upon a power-drill D of the usual form and construction or upon any other suitable portable tool having a rotatable spindle F. As shown in the drawings, the tool D is in the form of a pneumatic drill of usual construction, the body portion of which is cylindrical, as at C, and formed at one end with the usual removable cap and a handle H, the rotary spindle F being at its opposite end and having a socket *f* to receive a drill or the like.

The device or attachment 1 comprises a substantially cylindrical body portion 2, which is formed, preferably, of sheet metal and is divided longitudinally, as at 4, to permit its edges to be adjusted toward and from each other to vary the diameter of the body. This adjustment is preferably effected, as shown in Fig. 4, by providing projecting lugs 5 adjacent to the edges 4 of the body 2 and by providing a set-screw 6, which extends through a threaded opening in one of said lugs and has its inner end engaged with the other. The lugs 5 are removably mounted in brackets 7, which are secured adjacent to the edges of the body 2, so that when the screw 6 is turned in the proper direction the body 2 will be expanded to clamp a sanding or rasping surface upon its outer face. The sanding-face is clearly shown in the first two figures of the drawings and consists of a cylinder 8 of felt or other suitable cushioning material, which is covered with sand cloth, paper, or the like 9. When the attachment is to be used for rasping purposes, a cylinder 10 (shown in Fig. 5) is substituted for the sanding-cylinder. The cylinder 10 is of metal and has its outer face 70 roughened, as shown at 11, or in any other suitable manner, so that it may be used as a rasp. It will be understood that the adjustment of the edges 4 of the body 2 is very slight, so that the working face of the tool is at all 75 times cylindrical. The body 2 is secured at suitable points by means of screws or the like 12 two removable heads 13 14. The latter are open or in the form of spiders, each consisting of a hub 15 and a rim 16, connected by radial arms 17. The opening in the hub 15 of the head 13 is of sufficient size to receive the cylindrical portion C of the drill D, upon which portion said head revolves. On the outer face of the hub of the head 14 is formed 80 a stub-shaft 18, which has mounted upon it a handle 20, and on the inner face of said hub is an inwardly-projecting shank 21, adapted to be secured in the socket *f* of the rotary drill-spindle F.

In Fig. 6 I show a modified construction in which heads are formed integrally with the cylinder. When this is done, the shank 21 is the only point of connection of the attachment to the drill, the inner end of the attachment being open to permit of ready access to any part of the drill D, as will be seen.

The construction, use, and advantages of

the invention will be readily understood from the foregoing description, taken in connection with the accompanying drawings. It will be seen that the device or attachment 5 may be readily applied to any style of portable power-drill and that it may be used in various ways. By grasping the handles 20 and H the rotating body portion of the attachment with its sanding or rasping face 10 may be readily moved over the surface to be operated upon.

Various changes in the form, proportion, and the minor details of construction may be resorted to without departing from the principle or sacrificing any of the advantages of the invention.

Having thus described the invention, what I claim as new, and desire to secure by Letters Patent, is—

20 1. A rasping and sanding tool comprising a longitudinally-slit cylinder, an abrasive cylinder on the slit cylinder, brackets 7 on the inner side of the slit cylinder, at the ends thereof and on opposite sides of the slit there-

in, lugs 5 in the said brackets and projecting 25 beyond the ends of the slit cylinder, and set-screws connecting the said lugs, substantially as described.

2. A rasping and sanding tool for use in connection with a rotary power hand-drill, 30 and comprising a cylinder having a longitudinal split on one side, an abrasive cylinder on the split cylinder, means to diametrically expand and contract the split cylinder, and removable heads in said split cylinder, one of 35 said heads having a central opening to form the bearing for the cylindrical portion of the power-drill and the other having a bearing for the shank of a handle for attachment to the drill-spindle.

In testimony whereof I have hereunto set my hand in presence of two subscribing witnesses.

ERNEST K. McCOY.
